(57) **CLAIM**

The ornamental design for a baseboard heater cover, as shown and described.

DESCRIPTION

FIG. 1 is a perspective view of the baseboard heater cover our new design, showing it situated in relation to a conventional baseboard heater.

FIG. 2 is a front elevational view thereof.

FIG. 3 is a back elevational view thereof.

FIG. 4 is an elevational view of the right side thereof. The elevational view of the left side is a mirror image thereof; and,

FIG. 5 is a top plan view thereof. The bottom plan view is a mirror image thereof.

The baseboard heater shown in broken lines in FIG. 1, is an environmental element, and forms no part of our invention.
